DRILL PIPE STABILIZER AND GUIDE BUSHING

Lynn W. Storm, Austin, Tex.

Application February 23, 1954, Serial No. 411,918

6 Claims. (Cl. 255—27)

This invention relates to a drill pipe stabilizer and guide bushing, and more particularly to a device for application to a rotary drill stem and which is engageable with the interior of the bore of a well to guide and center the drill stem therein.

In the rotary method of well drilling the downward progress of the drill bit is opposed by tremendous forces depending on the type of bit, hardness or toughness of formation, depth of the well, and many other factors. The drill pipe employed in rotary drilling is the sole physical connection between the bit and the prime mover at the well surface, so that all the hammering, beating, twisting, and turning that the bit endures must first be borne by the drill pipe. In addition to the abuse that the bit suffers the drill pipe is exposed to various other stresses. One of the most severe stresses imposed on the pipe is the accumulated torque as a result of friction due to the rotation of the drill collars and pipe in contact with the interior of the well bore. This factor is influenced by the relation of hole size to pipe size, crookedness of the hole, coefficient of friction between pipe and formation and many other factors. Another form of stress suffered by the drill pipe, and often a cause of pipe failures, is the unavoidable wobbling in the string as it rotates. The wobble or transverse flexing is more pronounced in portions of the hole in which the course of drift changes in direction where a joint of pipe has a slight kink or bend, and at the lower end of the string where the pipe is in neither tension nor compression; the flexing point being dependent on the amount of weight bearing on the bit.

Another difficulty frequently encountered in the drilling of wells by the rotary process is the formation of key seats in the well bore due to the curvature of the bore and the engagement of the joints of the drill stem with the wall of the bore at the location of such curves, such joints being of smaller diameter than the drill bit, so that such key seats are of substantially smaller diameter than the diameter of the bore. A key seat may be formed in a hole by the broaching action of the drill pipe joints as they pass around curves or crooked spots on trips in and out of the hole. In removing the drill pipe from the hole there is a tendency for the pipe to be pulled in a straight line since the pipe is in tension, and any point in the hole not on this straight line will eventually be worn back by the dragging of the joints. The resultant broached portion of the hole is of the approximate diameter of the joints which is substantially less than the diameter of the drill bit. Thus, a key seat constitutes an undesirable hole condition likely to cause sticking of the drill pipe on trips out of the hole.

The present invention has for an important object the provision of means adapted to be connected into a drill pipe or string, whereby the above difficulties in carrying out well drilling operations by the rotary drilling process may be overcome and by which a substantial reduction may be accomplished in the stress and strain imposed on the drill pipe due to friction and wobbling of the drill pipe in the well bore.

Another object of the invention is to provide a drill pipe stabilizer and guide bushing by which the drill collars and pipe may be maintained in a centered position in the well bore to aid in the drilling of a straight as well as a vertical hole, and which may also serve to guide the drill collar and bit past a key seat or to wipe or ream the key seat in the event that it becomes necessary to do so.

A further object of the invention is the provision of a drill collar stabilizer and guide bushing which is constructed to rotate freely relative to the drill stem to which it is applied, and which may also be operated to cause the device to rotate with the drill stem for use as a key seat wiper or reamer when desired.

Another object of the invention is to provide a drill collar stabilizer and guide bushing device, which may also be operated as a key seat reamer and in which the operating parts of the device are protected against abrasion or other injury due to exposure to well fluid or contact with other foreign matter.

A further object of the invention is the provision of a drill stem stabilizer and guide bushing which is capable of operation to perform a jarring action in the event of sticking of the device in the well bore, to effect the release of the device or to facilitate its action in wiping or reaming out a key seat.

A still further object of the invention is the provision of a drill collar stabilizer and guide bushing which is of simple design and rugged construction, capable of withstanding the extreme conditions of wear and hard usage to which such equipment is customarily subjected.

The above and other important objects and advantages of the invention will best be understood from the following detailed description, constituting a specification of the same, when considered in conjunction with the annexed drawings, wherein—

Figure 1 is a vertical, central, cross sectional view of a preferred form of the invention showing the same as applied to a drilling string and illustrating the manner in which the same operates in a well bore as a stabilizer;

Figure 2 is a cross-sectional view, taken along the line 2—2 of Figure 1, looking in the direction indicated by the arrows;

Figure 3 is a view similar to that of Figure 2 illustrating one way in which the invention may be operated to enlarge a key seat in a well bore;

Figure 4 is a view similar to that of Figure 1, illustrating a modified form of the invention;

Figure 5 is a cross-sectional view, taken along the line 5—5 of Figure 4, looking in the direction indicated by the arrows;

Figure 6 is a side elevational view, partly broken away and partly in cross section, of the form of the invention illustrated in Figure 4, showing the relationship of the parts when the device is in condition to perform a reaming operation; and

Figure 7 is a view similar to that of Figure 1 illustrating a different form of the invention.

Referring now to the drawings in greater detail, the invention, as illustrated in Figures 1, 2, and 3, comprises an outer tubular casing 10, through which an inner tubular mandrel 12 extends, the mandrel being provided at its upper end with an internally threaded box portion 14, for the connection thereto of the lower end of an upper section 16, of a drilling string, and being externally threaded at its lower end, as indicated at 18, for the connection thereto of a coupling element 20, by which the mandrel may be connected to the upper end of a lower section 22, of the drilling string, or to a drill collar or other device located below the mandrel.

The mandrel may be provided with longitudinally spaced sets of radially extending external teeth or splines, 24 and 26, and the casing 10 has internal radially extend-

ing teeth or splines 28, located mediate its ends, which are adapted to be intermeshed with either of the sets of external teeth 24 and 26, or which may occupy a position between the sets of teeth and out of engagement therewith.

The mandrel 12 is of substantially smaller external diameter than the internal diameter of the casing 10, whereby the mandrel will be spaced radially inwardly from the casing, and the casing is preferably provided at its ends with internal counterbores 30, forming packing glands, within which suitable packing, such as that indicated at 32 is disposed, to form a fluid tight seal between the interior of the casing and the exterior of the mandrel. The ends of the casing are also internally threaded, as indicated at 34, for the reception of suitable screw plugs 36, which are engageable with the packing 32 to maintain the same in sealing engagement with the mandrel and casing.

The mandrel 12 is of substantially greater length than the casing 10, so that the mandrel may be moved upwardly or downwardly in the casing to engage or disengage the external teeth 24 or 26 with the internal teeth 28 of the casing. Within the casing, surrounding the mandrel 12, resilient elements 38 and 40, such as coiled springs, may be provided, which bear at their inner ends on suitable bearings, such as the ball bearings indicated at 42 and 44, respectively, and whose outer ends bear against suitable spring plates 46, seated in the counterbores 30, whereby the casing 10 is normally maintained with its internal teeth 28 out of engagement with the external teeth 24 and 26 of the mandrel. The bearings 42 and 44 are of conventional construction and of a size to provide clearance for the passage of liquid within the casing past the bearings, whereby when the interior of the casing is filled with liquid the inner and outer parts of the structure may be moved longitudinally relative to each other, without substantial resistance by such liquid.

External cutters 48, of suitable shape and arrangement, may be provided on the casing 10, by which the device may be operated as a reamer when desired.

Suitable detent mechanism may be provided for yieldingly maintaining the casing substantially centered longitudinally of the mandrel, to prevent undesirable vibratory movement of the casing on the mandrel, such detent mechanism preferably taking the form illustrated in Figure 2 of the drawings, wherein the casing is provided with one or more openings 50, in which balls 52 are positioned, for engagement in an annular raceway 54 in the outer surface of the mandrel, the balls being urged inwardly toward the mandrel by coil springs 56, which are retained in position by screw plugs 58 closing the openings.

The interior of the casing between the packing elements 32 within the counterbores 30 is adapted to be completely filled with a suitable liquid, such as oil, whereby the entrance of foreign material from the well bore into the interior of the casing is prevented.

In making use of the invention, constructed as described above, the mandrel 12 is connected into the drilling string, in the manner illustrated in Figure 1, with the casing 10 located substantially centrally longitudinally of the mandrel, in which position the teeth 24 and 26 of the mandrel will be out of engagement with the internal teeth of the casing. The device is then lowered into the well bore, indicated at W, whereupon the drilling string will be guided in the well bore, and held out of contact with the wall of the bore by the engagement of the cutters 48 with the wall of the bore. In this condition of the apparatus it will be evident that the casing and mandrel may rotate freely relative to each other, so that the device operates as a guide and stabilizer to promote the drilling of the well in a straight line, and to maintain the drilling string out of contact with the wall of the well bore.

In the event that a key seat has been formed in the

well bore, such as that indicated at K in Figure 3, of the drawings, the drill collar will be guided past the key seat and prevented from entering the same by the engagement of the cutters 48 with the wall of the key seat, whereby the drill collar will be prevented from becoming stuck in the key seat.

Under some circumstances, it may be desirable to rotate the casing with the mandrel to perform a reaming operation, as when the device becomes stuck in a key seat, or encounters some other obstruction in the well bore. In this event, upon engagement of the cutters 48 in the key seat, or with the obstruction, the casing will be held against longitudinal movement in the well bore, and by raising or lowering the drilling string the mandrel 12 may be moved longitudinally relative to the casing to bring the teeth 24 or 26 of the mandrel into meshing engagement with the internal teeth 28 of the casing, whereupon the casing will be caused to rotate with the mandrel to ream out the key seat or obstruction. By suitably regulating the length of the mandrel 12 the relative longitudinal movement between the mandrel and the casing may be limited, so that the casing will be in engagement with the box portion 14 of the mandrel when the teeth 26 are in meshing engagement with the teeth 28, and the casing will be in engagement with the coupling element 20 when the teeth 24 are in meshing engagement with the teeth 28.

It will be apparent that the mandrel 12 may be moved either upwardly or downwardly relative to the casing to couple the casing to the mandrel for rotation therewith, so that the device may be employed for reaming upwardly or downwardly, as may be necessary or desirable.

Should the casing 10 become stuck in the well bore the drilling string may be operated to perform a jarring action thereon. This may be accomplished by moving the string upwardly with the external teeth 26 of the mandrel, and the internal teeth 28 of the casing positioned for endwise abutting engagement. When the teeth 26 and 28 are thus engaged, an upward pull may be exerted on the string to place the string under tension and the string may then be rotated in either direction until the teeth 26 ride off of the teeth 28, whereupon the mandrel will move upwardly relative to the casing to engage the coupling element 20 with the lower end of the casing to produce an upward jar on the casing. Similarly, the string may be moved downwardly with the teeth 24 of the mandrel and teeth 28 of the casing positioned for endwise abutment until the string has been placed under compression, whereupon the string may be rotated to cause the teeth 24 to ride off of teeth 28, and the mandrel will then move downwardly to engage box 14 with the upper end of the casing to produce a downward jarring action on the casing.

By upward or downward movement of the drilling string the casing may also be engaged with the coupling element 20 or with the box portion 14 to produce a jarring action on the casing to release the same in the event of sticking of the casing in a key seat or other obstruction in the well bore.

It will thus be seen that the invention, as described above, combines a drill pipe stabilizer and guide bushing, which is simple in construction, and wherein the parts of the mechanism are entirely enclosed and protected against abrasion or other injury, and which is also operable when desired, by manipulation of the drilling string to perform both reaming and jarring operations.

A modified form of the invention is illustrated in Figures 4, 5, and 6, wherein the mandrel 12' has only one set of external teeth 26' arranged for meshing engagement with the internal teeth 28' of the casing 10', and only a single coil spring 38' is provided, which is located to coact with the mandrel and casing to yieldingly urge the casing upwardly on the mandrel to a position in which the teeth 26' and 28' are out of engagement, as

seen in Figure 4. The spring 38' bears at its upper end against the spring plate 40' and at its lower end against an external enlargement 66 formed on the mandrel. Bearing means, such as the ball bearings indicated at 62 may also be provided, which are positioned on the lower plate 46'. In other respects the parts of this form of the invention are similar to those previously described in connection with the form of the invention illustrated in Figure 1.

This form of the invention is used in a manner similar to that previously described, the mandrel 12' being connected to the lower end of an upper section 16 of the drilling string and to the upper end of a lower section of the same.

During the drilling operation, the parts will be in the positions indicated in Figure 4, the teeth 26' and 28' being out of engagement and the casing 10' being freely rotatable on the mandrel to act as a stabilizer. Upon upward movement of the string, as when the drill is being withdrawn from the well bore, should a key seat or other obstruction be encountered by the casing 10', the string may be moved upwardly relative to the casing, compressing spring 38' and bringing the teeth 26' and 28' into intermeshing engagement, as shown in Figure 6, whereupon the casing may be rotated with the string to effect a reaming action.

If desired a jarring action may be carried out with this form of the invention by moving the string longitudinally relative to the casing with the teeth 26' and 28' in position for endwise abutment, whereupon the string may be placed under tension and upon rotation of the string the teeth 26' may be caused to ride off of the teeth 28' so that the mandrel will be moved relative to the casing to effect a jarring action thereon.

A still different form of the invention is illustrated in Figure 7, which is somewhat similar in construction to that illustrated in Figures 4, 5, and 6, but wherein the pressure of fluid in the drilling string is utilized to operate the device. In this form of the invention the mandrel 12" has an upper portion 66 which is of smaller diameter than the lower portion 68 thereof, and an opening 70 is provided, which leads from the interior of the mandrel and opens into the interior of the casing 10". By this means it will be evident that the cross-sectional area of the space within the casing 10" at its upper end will be greater than the cross-sectional area within the casing at its lower end, and by the introduction of fluid under pressure into the casing from the string through the opening 70, the casing will be caused to move upwardly on the mandrel to a position in which the teeth 26" and 28" are disengaged.

In making use of the form of the invention illustrated in Figure 7, the device is connected into the string in the same manner as the forms of the invention previously described and the pressure of fluid in the string during normal drilling operation will enter the casing 10" through opening 70 and maintain the parts in the condition shown in Figure 7, whereby the mandrel may rotate freely in the casing.

In the event of sticking of the casing in the well bore, it be desired to couple the casing to the mandrel for rotation therewith to perform a reaming operation, the pressure of fluid in the string may be reduced, whereupon the mandrel may be moved upwardly relative to the casing to bring the teeth 26" into intermeshing engagement with the teeth 28" to cause the casing to be rotated with the mandrel. This form of the invention may also be operated in the manner previously described to effect a jarring action on the casing when desired.

The invention has been described herein in connection with a specific embodiment of the same, but it will be understood that this is intended by way of illustration only, and that numerous changes can be made in the construction and arrangement of the various parts, with-

out departing from the spirit of the invention, or the scope of the appended claims.

Having thus clearly shown and described the invention, what is claimed as new and desired to secure by Letters Patent is:

1. A device of the character described comprising inner and outer tubular parts movable longitudinally relative to each other, means for connecting the inner part to an operating string, means positioned between and engageable with the parts to hold the inner part in radially inwardly spaced relation to the outer part to form an annular chamber between the parts, sealing means between the parts at the ends of said chamber, abutment means on the inner part located exteriorly of the outer part in position for engagement with the ends of the outer part upon relative longitudinal movement of the parts in either direction to limit such movement, yieldable means in said chamber positioned to coat with the parts to yieldingly hold the outer part in a centralized position between said abutment means, interengageable means on the parts in the chamber positioned to be out of engagement when said outer part is in said centralized position to permit relative rotation of the parts and to be in engagement when said outer part is out of said centralized position in either direction to hold the parts against relative rotation and means on said outer part shaped to engage the surrounding wall of a well bore to hold said outer part centralized in said bore.

2. A device of the character described comprising inner and outer tubular parts movable longitudinally relative to each other, means for connecting the inner part to an operating string, means positioned between and engageable with the parts to hold the inner part in radially inwardly spaced relation to the outer part to form an annular chamber between the parts, sealing means between the parts at the ends of said chamber, abutment means on the inner part located exteriorly of the outer part in position for engagement with the ends of the outer part upon relative longitudinal movement of the parts in either direction to limit such movement, yieldable means positioned for engagement with the parts in said chamber to yieldingly hold the parts in a central position longitudinally relative to each other, interengageable means on the parts in the chamber positioned for engagement upon relative longitudinal movement of the parts in either direction from said central position to hold the parts against relative rotation and for disengagement when the parts are in said central position to permit such relative rotation and external means on said outer part positioned to engage the surrounding wall of a well bore to hold the outer part centralized in said bore.

3. A device of the character described comprising inner and outer tubular parts movable longitudinally relative to each other, means positioned between and engageable with the parts to hold the inner part in radially inwardly spaced relation to the outer part to form an annular chamber between the parts, sealing means between the parts at the ends of said chamber, interengageable means on the parts in the chamber positioned for disengagement upon relative longitudinal movement of the parts to one position to permit relative rotation of the parts and for engagement upon relative longitudinal movement of the parts to another position to hold the parts against such relative rotation, yieldable means in the chamber positioned to coat with the parts to yieldingly hold the parts against relative longitudinal movement from said one to said other of said positions and radially extending external cutting means on said outer part whose outer ends are shaped to engage the surrounding wall of a well bore to hold said outer part centralized in said bore, said cutting means being shaped to enter a keyseat in said bore and to perform a cutting action on the wall of the bore in said keyseat upon rotation of said outer part in said keyseat.

4. A device of the character described comprising in-

inner and outer tubular parts movable longitudinally relative to each other, means positioned between and engageable with the parts to hold the inner part in radially inwardly spaced relation to the outer part to form an annular chamber between the parts, sealing means between the parts at the ends of said chamber, interengageable means on the parts in the chamber positioned for movement to a disengaged position upon relative longitudinal movement of the parts to one position to permit relative rotation of the parts and to an engaged position upon relative longitudinal movement of the parts to another position to hold the parts against relative rotation, yieldable means in the chamber positioned to coact with the parts to yieldingly hold the parts against relative longitudinal movement in a direction to move said interengageable means from said disengaged position to said engaged position and external means on said outer part positioned to engage the surrounding wall of a well bore to hold said outer part centralized in said bore.

5. A device of the character described comprising inner and outer tubular parts movable longitudinally relative to each other, means positioned between and engageable with the parts to hold the inner part in radially inwardly spaced relation to the outer part to form an annular chamber between the parts, sealing means between the parts at the ends of the chamber, interengageable means on the parts in the chamber positioned for movement to an engaged position upon relative longitudinal movement of the parts to one position to hold the parts against relative rotation and to a disengaged position upon relative longitudinal movement of the parts to another position to permit relative rotation of the parts, yieldable means in the chamber positioned to coact with the parts to yieldingly hold the parts against relative longitudinal

5 movement in a direction to move said interengageable means from said disengaged to said engaged position and external radially extending cutter means on said outer part positioned to engage the surrounding wall of a well bore to hold said outer part centralized in the bore and shaped to enter a keyseat in said bore and to perform a cutting action on the wall of the bore in the keyseat upon rotation of the outer part in the keyseat.

6. A device of the character described comprising inner and outer tubular parts movable longitudinally relative to each other, means positioned between and engageable with the parts to hold the inner part in radially inwardly spaced relation to the outer part to form an annular chamber between the parts, sealing means between the parts at the ends of the chamber, yieldable means in the chamber positioned to coact with the parts to yieldingly urge the parts toward a predetermined longitudinal position relative to each other, interengageable means on the parts in the chamber positioned to be engaged upon relative longitudinal movement of the parts away from said predetermined position to hold the parts against relative rotation and to be disengaged upon relative longitudinal movement of the parts into said predetermined position to permit relative rotation of the parts and external means on said outer part positioned to engage the surrounding wall of a well bore to hold the outer part centralized in said bore.
